UNITED STATES PATENT OFFICE

2,207,390

INJECTOR HEATER

John C. White, Madison, Wis.

Application July 31, 1939, Serial No. 287,450

2 Claims. (Cl. 261—76)

This invention relates to apparatus for heating fluids by means of steam, either live or exhaust, and constitutes an improvement upon the heater disclosed in my Patent No. 2,066,867, issued January 5, 1937.

With the use of a heater such as disclosed in said patent, the temperature of the fluid being heated can be raised only approximately to a maximum of 165° F., because the relation of steam to waterflow in the injector proper must be such as to maintain a vacuum of about 20 inches mercury at the throat of the venturi or combining tube, and any attempt to attain a final temperature above 165° F. by increasing the steam relatively to the amount of water introduced will so reduce the vacuum at the throat of the venturi as to cause unstable and unsatisfactory operation.

The primary purpose of my present invention is to provide an injector heater by which the liquid being heated may be raised to a temperature considerably above the maximum of 165° F. heretofore attainable. In fact, my present invention is capable of delivering the effluent at a temperature higher than 200° F., and in actual tests an effluent temperature of 210° F. has been attained. For certain purposes, such as milk drying and other processes, such high temperatures are very desirable, and the requirements of such methods may be met by employing an injector heater constructed in accordance with the principles of my present invention.

While my invention is capable of many uses, it is here shown for illustrative purposes as incorporated in a heat exchange system of the general type exemplified in my prior Patent No. 2,158,809, issued May 16, 1939.

Referring to the accompanying drawing,

Fig. 1 is a perspective view of a heat exchange system embodying my improved injector heater;

Fig. 2 is a longitudinal sectional view of a heater constructed in accordance with my invention; and

Fig. 3 is a transverse sectional view on the line 3—3 of Fig. 2.

The system chosen for the purposes of exemplifying the principles of my invention and illustrated in Fig. 1 is similar to that disclosed in my prior Patent No. 2,158,809, and comprises a heat exchanger 4 of the double pipe type in which the outer pipes conduct the heating fluid around the inner pipes containing the fluid to be heated. A storage tank 5 supplies a constant head of water for the injector heater 6 to which the water from the tank is conducted by a pipe

1 and from which the heated water is conducted to the lowermost coil of the heat exchanger by a pipe 8.

A steam supply line 9 carrying either live or exhaust steam is provided with a thermostatically controlled valve 11 for regulating the flow of steam through the pipe 12 to the heater which heats and simultaneously propels the water through pipe 8 to the coils. The water emerges from the coils into a pipe 13 by which it is returned to the storage tank. The tank is equipped with an overflow pipe 14 and a supply pipe 15 equipped with a float controlled valve 16. The fluid to be heated is supplied to the heat exchanger through pipe 17, and the flow of heating fluid to the exchanger is controlled through a diaphragm actuated valve 18 by the flow of fluid through pipe 17. Further details of the apparatus need not be described here, as they are fully disclosed in said Patent No. 2,158,809.

The injector heater 6, by which the water delivered from the tank 5 through the pipe 7 is heated by the steam delivered to the heater from the pipe 12, comprises as shown in Fig. 2 a combining tube 19 and a delivery tube 21 having their opposed ends maintained in spaced relation by a cylindrical sleeve 22 which provides an overflow chamber from which the overflow is delivered through a pipe 23. The steam entering from pipe 12 is delivered into the intake end of the combining tube 19 through a nozzle 24 projecting through a chamber 25 to which the water is supplied by the pipe 7. The water is drawn by the injector action of the delivered steam into the combining tube, with the result that the steam and water are combined during their travel therethrough, the water being heated by absorbing the heat units of the steam and the steam being at the same time condensed. The combined flow of heated water is discharged at high velocity across the gap between tubes 19 and 21 in overflow chamber 22. Entering the delivery tube 21, its velocity head is gradually converted to pressure head and it emerges through pipe 8 to the point of use.

The construction of the heater thus far described is similar to that disclosed in my Patent No. 2,066,867, but as previously stated, it is impossible with this heater to attain a delivery temperature of the effluent in excess of approximately 165° F. For the purpose of increasing the delivery temperature of the effluent without detracting from the efficiency of the heater, my present invention contemplates further heating the effluent by delivering steam thereto in the

low pressure area of the delivery tube, that is, the vicinity of the Venturi throat and preferably just rearwardly of the throat where a partial vacuum exists so that the introduction of the steam has no appreciable effect on the mechanical action of the injector.

With this end in view, the tube 21 is formed to provide a chamber 26 surrounding the bore of the tube and communicating therewith through an annular passage 27, the chamber being supplied with steam through a connection 28 communicating through a pipe 29 with the steam supply pipe 9. The steam thus supplied is drawn into the delivery tube and further heats the liquid flowing therethrough so that the temperature of the delivered effluent is raised from a previous maximum of 165° F. to a temperature above 200° F. and closely approaching the boiling point of 212°.

20. The steam supply pipes 9 and 29 are equipped with hand operable shut-off valves 31 and 32, respectively. In starting the operation, valve 32 is closed, and valve 31 is opened to admit steam to the heater in proportions determined by the temperature controlling valve 11 so as to deliver the heated fluid to pipe 8 from the heater at a temperature not over 165° F., which is the maximum temperature at which an injector heater could normally be operated prior to my invention.

30. In order to obtain a higher temperature, the valve 32 is gradually opened admitting supplementary steam to the delivery tube through the annular passage 27 until the desired final temperature is attained. When set for the desired temperature, the system will continue to operate automatically without further attention.

The structural details of the heater may of course be varied within considerable limits without departing from the scope of the invention as defined in the following claims.

out departing from the scope of the invention as defined in the following claims.

I claim:

1. An injector heater having a Venturi passage comprising a tapered combining tube forming an intake at its larger end and a tapered delivery tube forming an expanding portion for the passage, the said expanding portion having an area of low pressure during operation of the injector, said tubes being arranged in alignment with their smaller ends adjacent to each other, an overflow chamber surrounding the adjacent ends of said tubes, means for supplying to the intake end of said combining tube the liquid to be heated and steam for heating the same, and means for introducing additional steam into the low pressure area of the expanding portion of the passage close to the overflow chamber.

2. An injector heater having a Venturi passage comprising a tapered combining tube forming an intake at its larger end and a tapered delivery tube forming an expanding portion for the passage, the said expanding portion having an area of low pressure during operation of the injector, said tubes being arranged in alignment with their smaller ends adjacent to each other, an overflow chamber surrounding the adjacent ends of said tubes, means for supplying to the intake end of said combining tube the liquid to be heated and steam for heating the same, an annular chamber surrounding the bore of the expanding portion of said passage close to the overflow chamber and communicating with the low pressure area of the passage, and a steam supply connected with said annular chamber for introducing additional steam into the passage.

JOHN C. WHITE.
